UNITED STATES PATENT OFFICE.

CHESTER A. FRICK, OF MUNCIE, INDIANA, ASSIGNOR TO GLASCOCK BROTHERS MFG. COMPANY, OF MUNCIE, INDIANA, A CORPORATION OF INDIANA.

REFRIGERATOR.

Application filed November 16, 1927. Serial No. 233,532.

My invention relates to improvements in refrigerators primarily designed for the cooling of bottled drinks.

One of the objects of my invention is to 5 provide a refrigerator for the storage of bottled drinks which will occupy a relatively small space, which may be cheaply manufactured and which, while being cheap from a construction standpoint, will be efficient in 10 the cooling of the bottled goods.

For the purpose of disclosing my invention I have illustrated one embodiment thereof in the accompanying drawings, in which—

15 Fig. 1 is a front view of a refrigerator embodying my invention;

Fig. 2 is a side elevation thereof;

Fig. 3 is a longitudinal section;

Fig. 4 is a transverse section;

20 Fig. 5 is an enlarged detail section of the upper edge;

Fig. 6 is an enlarged detail section showing the manner of securing the legs in position, and

25 Figs. 7 and 8 are detail sections showing the means for mounting the bottle dividers.

In the embodiment of the invention illustrated, a rectangular outer casing is formed comprising side and end panels 1 which are

30 connected together at their meeting edges by corner angles 2, which angles provide not only means for connecting the panels together, but add to the trim of the structure. These angles are preferably secured to the

35 panels by bolts or screws. Each of the panels 1 at its bottom, is inturned as at 3 and is provided with a down-turned lip 4. Fitting within the bottom opening thus formed is a bottom closure 5 having a down-turned flange 6 lying parallel with the lip 4 and having an up-turned lip 7 which overlaps the edge of the lip 4, the metal of the lip 7 being crimped upon the lip 6 to hold the bottom in position.

40 This casing is adapted to be supported on legs preferably in the form of angle members 8, the upper ends of which are inturned at 9 and which are secured to the bottom of the casing by means of screws 10

45 adapted to be passed through the inturned flanges 3 and into corner angles 11 arranged within the corners of the casing, these angles being secured in position by the bolts 12, which bolts also assist in securing the angles

50 2 in position. This construction permits of

the ready removal of the legs in event it is desired that the structure be placed on a counter or table.

Nesting within the outer casing is an inner open-topped tub, the side walls 13 and the bottom 14 of which are spaced apart from the outer casing, which spacing is filled with suitable insulating material, such for instance as ground cork or the like. The walls 13 are slightly shorter than the 55 outer panels and the exposed edges of the walls are covered by a top cap, one on each edge, comprising the flat plate 15 having a down-turned flange 16 overlying the walls 13 and an up-turned flange 17 lying parallel 60 with the upwardly extending portion of the panels and fitting over this portion is a U panel 18, the inner wall 19 of which is spaced from the wall of the tub to provide a ledge 20.

75 The inner tub is divided into an ice chamber 21 and a bottle chamber 22, by means of a transversely extending wall 23, the upper end of which is provided with a cap member 24 having out-turned flanges 25 and 26 70 serving as supports at this point for the covers for the ice chamber and bottle chamber. The bottle chamber is divided into a plurality of longitudinally extending channels for the reception of bottles by means of longitudinally extending rods 27, the ends of which are down-turned at 28 and at one end of the rod take into sockets 29 formed by a strip 30 secured to the dividing wall 23 and at their opposite end into sockets 31 80 formed by a similar strip secured to the front wall of the tub. By this construction the members dividing the bottle chamber into channels also add in the spacing and maintaining in position of the transversely 85 extending divider 23. It should be noted that this divider 23 is provided with openings 32 therein to permit the liquid from the ice chamber 21 to flow into the bottle chamber 22.

90 95 100 The bottle chamber is closed by a suitable cover 33 comprising a pair of spaced apart metal walls containing between the same insulating material and this cover is hinged at its center as at 34 to permit one section of the cover to be raised at a time.

105 110 The ice chamber is closed by a cover 35 of a similar double wall construction, which cover at its opposite ends is provided with handles 36 adapted to extend materially up-

wardly from the top of the cover and receive between the same a shallow receptacle 37 in which may be placed bottles for display and renewal purposes.

5 The ice chamber is suitably drained by a drain pipe 38 having drain openings 39 at their tops and at such a height as to maintain the water level in the ice and bottle chambers at a desired level.

10 I claim as my invention:

1. A bottle refrigerator comprising an outer casing and an inner receptacle, the walls of which are spaced apart from the walls of said outer casing, said spacing being filled with suitable insulating material, a transversely extending divider member removably mounted in said receptacle and means for dividing one of the compartments formed by said dividing member into run-

20 ways for bottles comprising longitudinally extending rods removably connected to the divider member and to the front wall of the receptacle and maintaining the divider member in properly spaced relation with respect

to the front and back walls of the receptacle. 25

2. A bottle refrigerator comprising an outer casing and an inner receptacle, the walls of which are suitably spaced and the spacing filled with insulating material, means for dividing said receptacle into two 30 compartments comprising a transversely extending removably mounted divider plate, an independent cover for each of said compartments and the upper edge of the plate fitting between said covers and having means 35 for supporting the adjacent edges of said covers and means for longitudinally dividing one of said compartments into bottle runways comprising longitudinally extending members removably connected to the 40 bottom of said dividing member and to the front wall of said receptacle.

In witness whereof, I, CHESTER A. FRICK, have hereunto set my hand at Muncie, Indiana, this 12th day of November, A. D. one 45 thousand nine hundred and twenty-seven.

CHESTER A. FRICK.
